UNITED STATES PATENT OFFICE

THOMAS W. MCNEILL, OF CHICAGO, ILLINOIS, ASSIGNOR TO REID, MURDOCH & CO., OF CHICAGO, ILLINOIS, A CORPORATION OF ILLINOIS.

SYSTEM FOR TRANSPORTING MATERIALS IN BULK.

1,089,851.

Specification of Letters Patent. Patented Mar. 10, 1914.

Application filed October 21, 1912. Serial No. 726,958.

To all whom it may concern:

Be it known that I, THOMAS W. MCNEILL, a citizen of the United States, residing at Chicago, in the county of Cook and State of Illinois, have invented certain new and useful Improvements in Systems for Transporting Materials in Bulk, of which the following is a specification.

My invention relates to improvements in systems for transporting materials in bulk.

It is especially designed for the transportation of pickles, or the like, that may be contained in brine, or other liquid, so that large quantities of such materials may be quickly handled and transported from one location to another and the brine, or other liquid, separated from such materials, while in transit and returned to its original reservoir, or otherwise disposed of.

One of the objects of my invention is to provide a system, and means of operation, whereby pickles, or the like, may be transported from one location in a factory to another and by means of which, the pickles, or such like articles, may be loaded in proper receptacles, as in cars or on board ship.

Other and further objects of my invention will readily appear to persons skilled in the art from a consideration of the description when taken in conjunction with the drawings, wherein:

Figure 1 represents a schematic arrangement in elevation, partly in section, showing my system as it appears when in operation; Fig. 2 is an enlarged, vertical central section of a receiving tank showing parts in dotted lines; Fig. 3 is an enlarged sectional view of a three-way valve controlling a conduit, communicating with said tank; Fig. 4 is an enlarged sectional view of a dash-pot for controlling the movement of the valve.

In all the views the same reference characters indicate similar parts.

10 is a tank, or other receptacle, containing pickles in brine, or like materials, in bulk, which may be located at any point from which it is desirable to transport the contents 11 of the tank.

12 is a hose, through which the materials are to be transported. It is connected to a conduit, or pipe 13, which may be permanently fixed in the premises, and which is provided, at proper intervals with T's 14 and 15. The T's that are not in use are

closed by screw caps or plugs 16. A screw cap 17 is attached to one terminal of the hose 12 and is adapted for engagement with the T's 14, whereby to connect the receiving hose to any of the T's along the line of the pipe 13. The pipe 13, is always closed except at the point where the apparatus is attached. A receptacle comprising a receiving tank 21 is provided with an open bottom and a closure 22 hinged thereto as at 23. The closure is provided with a packing 24, which serves to make an air tight joint between the closure and the bottom of the tank 21. A counterbalance weight 27 is adjustably secured to the lever 28 at proper distance from the point of fulcrum 23 so as to substantially over-counterweight the closure 22 so that it will automatically return to normally closed position shown in full lines in Fig. 2. An inlet nipple 30 is provided with an automatically closing valve 31, hinged as at 32, and provided with packing 33 to provide an air tight joint between the said valve and the nipple. A hose 34 is connected to the nipple 30 and is provided on its free end with a screw cap 35, for engagement with any one of the T openings 15.

The receiving tank 21, is connected, by means of a relatively small hose 36 with air pipe 37 which extends coextensively with and parallel with the transporting conduit or pipe 13. The pipe 37 is provided with a series of outlets 38 controlled by globe valves 39 to which the hose 36 is adapted to be connected. An air receiver, or tank 40, preferably of larger dimensions than the tank 21, is connected to the air pipe 37, by means of a pipe 42, controlled by globe valve 43. An air exhaust pump 44, driven by a wheel 45, is connected to the tank 40 by means of pipe 46 which is controlled by the globe valve 47. The valve 48 controls communication between the air pipe 37 and the tank 21.

When it is desirable to transport the contents of the receptacle 10, which may be located at any convenient distance, communication is established between the tank 40 and the tank 21 by means of the valve 48 and as the air has been all substantially exhausted from the tank 40, by means of the exhaust pump 44, there will be sufficient difference of pressure established between the exterior of the system and the interior there-

100

105

110

of, to cause the pickles, or other materials contained in the receptacle 10, to ascend the hose 12 into the transporting pipe 13 and through the said pipe to the hose 34, which 5 may be located at a remote distance from receptacle 10, into the tank 21, opening the valve 31 and filling the tank. As soon as the substantial vacuum has been established in the tank 21 the closure 22 will be held firmly 10 upon its seat, by the difference between the exterior and interior pressure, with sufficient force to hold and support the weight of the contents of the tank 21. The tank is pivotally supported on lever 50 as at 51, which 15 lever is pivoted to a carrier 52 as at 53. The outer end 54, of the lever 50, is connected by pivoted links 55 and 56 to the valve 48. In the position shown in full lines in Fig. 2, the valve 48 is so turned that the ports 59 20 and 60, (Fig. 3) provide a clear opening between the hose 36 and the tank 21, so that practically all of the air that has been contained in the tank 21 is immediately drawn out, by virtue of the partial vacuum established 25 in the tank 21, into the tank 40 and it is immediately pumped from the tank 40 by means of the pump 44 thereby establishing substantially a practical vacuum in the transporting conduit system.

30 When the tank 21 has been sufficiently filled with the articles the said tank and contents will substantially counterbalance, or overbalance, a weight 61 which is adjustable along the end 62 of the lever 50, the 35 weight 61 will be lifted, as shown in dotted lines in Fig. 2, until the lever 50 is brought into contact with the stop 78', at which time the valve 48 will be so moved that the port 63 will register with the opening in the 40 elbow 64 and the port 60 will register with the outside atmosphere through the pipe 65 and closing the opening communicating with the hose 36 and the vacuum tank 40, thus 45 breaking the vacuum, or releasing the pressure within the tank 21. After this has been done the closure 22 will be no longer held upon its seat 24, of the tank 21 and the weight of the contents will cause the closure to open, as shown in dotted lines in Fig. 2, 50 emptying the contents of the tank 21 upon a perforated, inclined table, or platform 66. The pickles, or other materials that are being transported, and were at this time contained in the receptacle or tank 21, will 55 therefore be deposited upon the incline 66 from which they immediately roll or fall upon the conveyer 67, which may be driven by the pulley 68, or other suitable means, and will be carried by such conveyer to a 60 desired destination. The liquid passing through the perforated platform or table 66, will be entrained through the pipe 69 back to the original receptacle, or other convenient disposition may be made of it, while 65 the pickles delivered to the conveyer 67 will

be in substantially a dry state in which condition they may be delivered to a receptacle in the factory, a cart, or to a car or other receptacle provided for them. After the closure 22 has been opened, in the manner 70 substantially as described, the valve 31 will be automatically seated and by this means the contents of the hose 12, and of the pipe 13, will remain undisturbed, otherwise the contents of these receptacles would be immediately discharged into or returned to the reservoir from which they had been removed, and the efficiency of the operation would be somewhat affected. As soon as the closure 22 is relieved of the weight of the 75 pickles, or other materials being transported, the counterbalance weight 27 will return it to its normal position closing the tank 21. It, however, requires some time for the closure to be returned and I, therefore, provide a retarding mechanism to delay the return of the tank 21 so that the closure 22 may have sufficient time in which to be properly seated upon the lower opening provided in the bottom of the tank 21. To this 80 end I provide a dash-pot 70, having a piston 71, connected by means of a link 72 to the lever 50 as at 74, where it is pivotally secured to the lever. It is also pivotally secured to the piston 71 as at 73. At the 85 bottom of the cylinder 70 is an air flap valve 75 normally covering an air opening 76. During the time when the tank 21 is descending this flap opens and permits air through the passage 76 to freely enter the 90 cylinder 70 and thus prevent the retarding effect that would be otherwise produced by means of the dash-pot. When the tank, or receptacle 21 is returning, however, to normal position after having been emptied of 95 its contents as shown in full lines in Fig. 2, the flap valve 75 will be seated and the air within the cylinder 70 will slowly leak through the pet cock 77 which is provided for this purpose, so that the time required 100 for the receptacle to reach its normal upward position may be varied by means of adjustment of the pet cock 77. A stop 78 retains the lever 50 in a predetermined position, so that the weight 61 can not raise the 105 receptacle farther than a prescribed distance allowed by this stop. As soon as the closure 22 has returned to its normal closed position, as shown in full lines in Fig. 2, the valve 48 will be again opened, as shown in 110 Fig. 3, establishing communication between the vacuum tank 40 and the tank 21 thereby withdrawing substantially all of the air contained in the tank 21 and once more establishing a partial vacuum therein which 115 will have the effect to discharge the contents of the hose 12 and 34 and the pipe 13 and cause other material to pass through this conduit until the tank 21 is again filled, when the same operations will be performed 120 125 130

and such operations will continue, automatically to be performed, so long as there is sufficient material within the tank 10 to maintain the substantial vacuum established within the transporting conduit.

A gage glass 79, is provided in the air receiver 40 so that any entrained water that may pass over and through the tank 21 into this receiver may be instantly indicated 10 through the glass and the contents of the tank removed.

An I beam track 80 is maintained in substantial parallelism with the pipes 13 and 37 and extends coextensively therewith, so 15 that the tank 21, when disconnected from the respective pipes may be moved along the I beam, by means of the trolley or carrier 52 to suitable positions for communication with other openings in the said pipes 20 and for delivery of the pickles or other materials to other selected points.

While I have herein described a single embodiment of my invention it is apparent that many changes may be made in the specific construction without departing from 25 the spirit and scope of the appended claims.

What I claim is:

1. A system of the character described, comprising, in part, a material-conveying 30 pipe, a receptacle for materials to be conveyed, means for connecting said pipe and said receptacle, a material-receiver open at the bottom and having a materials inlet port connected to said pipe, and air exhaust 35 means for said receiver, a valve for said port controlling communication between said receiver and conveying pipe, a valve for closing the bottom opening of said receiver by operation of atmospheric pressure and sup- 40 porting the contents of said receiver, and means operated by the contents of said receiver for admitting air therein and thereby relieving the atmospheric pressure to permit the bottom valve to open by the weight of 45 the contents of said receiver and seat the valve for the inlet port.

2. A system of the character described, comprising, in part, a material-conveying 50 pipe having a plurality of closable openings therein, and an air exhaust pipe having a plurality of closable openings therein, a trolley track coextensive and parallel with said pipes, a material-receiver having means for connection to both said pipes and having a 55 trolley for coöperation with said track whereby said receiver may be moved from place to place thereon, an atmospheric seated valve for closing a discharge opening in said receiver and for supporting the contents 60 thereof, a valve for controlling communication between said receiver and said air ex-

haust means, and means operated by the contents of said receiver for closing said exhaust valve and for opening communication between said receiver and the atmosphere, 65 thereby permitting the discharge valve to open and discharge the contents of said receiver.

3. A system of the character described for handling materials carried in a fluid medium, comprising, in part, a material container, a materials conveying pipe connected thereto, a material-receiver connected to said conveying pipe, an air-exhaust pipe communicating with said receiver, a valve 75 controlling said communication between the exhaust pipe and receiver, an air admitting valve, a closure for the bottom of said receiver, means responsive to presence of predetermined amount of material in said re- 80 ceptacle to operate the air-controlling valves thereto, a check valve closing toward the material-conveying pipe, and means to catch material and liquid discharged from said bottom opening upon admission of air to 85 said receiver.

4. A system of the character described, comprising, in part, an air-exhaust pipe, a material-conveying pipe, a receiver having communication with said two pipes, a valve 90 for controlling communication to the air-exhaust pipe, a closure for the receiver, means to support said receiver for movement operable upon admission of air to the receiver by the weight of a predetermined 95 amount of contained material, said means comprising a weighted lever, means for pivotally connecting said receiver to said lever, and means for operation of said valve upon movement of said receiver, means to return 100 the closure to closed position after opening, and a retard means, whereby the closure is moved to closed position before the opening of communication between the receiver and the exhaust pipe. 105

5. A system of the character described, comprising, in part, a material-receiver, a material supply pipe and an air-exhaust pipe communicating therewith, a mechanically-closable valve for the discharge opening of said material-receiver, a valve for controlling communication with the air-ex- 110 haust pipe, means for closing said valve to the air-exhaust pipe, and means for retard- 115 ing the opening of said valve till said mechanically closable valve is closed.

In testimony whereof I hereunto set my hand in the presence of two witnesses.

THOMAS W. McNEILL.

In the presence of—

W. LINN ALLEN,
MARY F. ALLEN.
